UNITED STATES PATENT OFFICE

JOHN ADAMS HOWELL, OF THE UNITED STATES NAVY.

IMPROVEMENT IN PROPULSION OF MARINE TORPEDOES.

Specification forming part of Letters Patent No. 121,052, dated November 21, 1871.

To all whom it may concern:

Be it known that I, JOHN ADAMS HOWELL, of the United States Navy, have invented certain Improvements in Marine Torpedoes, of which the following is a specification:

My invention has a double purpose, and is intended to be used in connection with that class of marine torpedoes known as self-propelling. It consists, first, in furnishing a torpedo with a fly-wheel, this fly-wheel to be moved by any power extraneous to the torpedo. It is to act as a repository of power, so that, on being detached from the moving force and launched in the water, the torpedo will be propelled by the inertia of the fly-wheel, acting through a screw or other propelling instrument. The second aim of my invention is to apply that portion of the inertia of the revolving wheel which tends to keep its axis of rotation unchanged to the counteracting of deviating forces. This is effected by giving the axis of the fly-wheel a particular direction in reference to the longitudinal axis of the torpedo. For instance, in launching a torpedo from the broadside of a vessel at full speed the first effect of the resistance of the water would be to turn the longitudinal axis in the horizontal plane. If provided with a rapidly-revolving fly-wheel whose axis is in the horizontal plane, the resulting motion would be in the vertical plane. As the forces of gravity and buoyancy act in this plane, by applying them we could prevent or diminish the deflection of the torpedo in launching. By using two concentric parallel fly-wheels

of equal inertia and revolving in opposite directions the resulting angular motion of the longitudinal axis would be reduced to a minimum.

The following is a general description of the accompanying drawing:

The figure is a section of the torpedo by any plane through its longitudinal axis.

c c c, &c., is the casing of the torpedo. *b b* is a stuffing-box, through which passes the propeller-shaft *s s s*. Secured to this shaft is the hollow cylinder *A*, which acts as a fly-wheel. *B B* are rings which support the journals of the shaft. Practically, it might be better to gear the fly-wheel to the propeller-shaft; also, in order to allow the torpedo motion about a transverse axis in order to change its direction when in the water, the axis of the fly-wheel should be perpendicular to the longitudinal axis of the torpedo. In case of gearing the fly-wheel to the shaft when the axes are in the same straight line, the reaction on the gears would give a rotary motion to the casing, in a contrary direction to that of the screw. To utilize this motion screw-blades must be placed on the outside of the casing.

I claim as my invention—

The combination of the fly-wheel and torpedo for the purpose of propelling the latter, as hereinbefore set forth.

JOHN ADAMS HOWELL.
